METHOD OF SUPPLYING FUEL FOR ENGINE
IDLINGArlington Moore, New York, N. Y., assignor, by
mesne assignments, to Maxmoor Corporation,
New York, N. Y., a corporation of Delaware

Application March 17, 1932, Serial No. 599,420

3 Claims. (Cl. 261—75)

My invention relates to methods of supplying fuel to internal combustion engines during engine idling, and the same has for its object to supply the fuel at a relatively constant rate over a wide range of variation of the intake depression effecting the introduction of the fuel, whereby to obtain smooth, steady idling operation.

Another object of the invention is to permit a variation of idling speed by controlling the air quantity without variation in the quantity of fuel supplied, rendering the engine idling stable under a broad tolerance of variations.

Another object of the invention is to enable adjustment of the mixture ratio for any desirable idling speed, while maintaining the rate of fuel flow for each adjustment substantially constant.

This application is a continuation-in-part of my application Serial No. 525,992, filed March 28, 1931, Patent No. 2,056,615, Oct. 6, 1936 and 20 of my application Serial No. 591,040, filed February 5, 1932, Patent No. 2,037,530, Apr. 14, 1936, the idling arrangement being illustrated herein associated with an ordinary carburetor, although the invention is adapted for use with various 25 types of carbureting means, such as those disclosed in my said prior applications.

In the accompanying drawing:

Figure 1 is a sectional elevation of one form of device constructed according to and embodying 30 my said invention; and

Fig. 2 is a detail sectional view of a modification, illustrating means provided for manual adjustment of air inlet orifice for control of discharge rate of fuel.

In the drawing, for purposes of illustration, my 35 idling arrangement is shown associated with a carburetor of the ordinary type in which the charge is throttled after admixture of the components thereof. This type of carburetor comprises an intake conduit 10, venturi 12, and main fuel jet 14 supplied with fuel from the float chamber 16, the admixture of fuel and air being effected at the venturi 12, and the mixture controlled by the mixture throttle 18.

I preferably supply the fuel for engine idling 40 independently of the main fuel supplied at other stages of operation, and at a relatively constant rate notwithstanding variations or fluctuations of intake depression.

To obtain such result I lift fuel in a solid liquid state through duct 20 from the constant level float chamber 16 into the bottom of a horizontal chamber or passage section 22 having a relatively weak pressure reduction therein obtained 45 by venting one end of the chamber 22 through

a highly constricted orifice 24 located at an intermediate point of the chamber either directly, or through suitable passages, into the intake at the engine side of the throttle 18, thereby rendering the orifice subject to the pressure reduction in 5 the intake conduit at the engine side of the throttle, and by venting the other end of the chamber 22 at substantially the same level to the atmosphere through orifice 26 preferably opening into the top of the bowl 16 which is 10 vented to atmosphere. This arrangement prevents the orifices 24 and 26 from clogging with dust or dirt.

The pressure reduction developed in chamber 22 at and near idling operation attains a value 15 which is relatively constant compared to the fluctuations in intake depression, this pressure reduction being sufficient to lift the fuel through passage 20 into the chamber 22 at the intake depressions prevailing at and beyond idling operation so that fuel is available at such stages of 20 operation.

The fuel thus lifted forms a fuel level in chamber 22 substantially on a line with orifices 24 and 26 leaving a space above the fuel level for 25 surface vaporization. The fuel surface in chamber 22 is subjected to the vaporizing effect of the air passing through orifice 26, and sweeping over the surface of the fuel to form, apparently, a compressible suspension of fuel in air. The distance between the orifices 24 and 26 is preferably 30 short enough to prevent the air sweeping over the surface of the fuel in chamber 22 from causing waves on or other surging of the fuel liable to submerge orifice 24 and cause excessive 35 fuel to pass into the intake. I have found that a desirable length for the chamber 22 is such that the meniscus of the fuel is substantially coextensive with such length, the surface of the fuel from end to end of the chamber being substantially 40 concave. The concave surface of the fuel under tension resulting from capillary effect is less liable to develop waves or other surges there- 45 in as a result of the air sweeping thereover, the action of the air in causing fuel vaporization being analogous to the action of a surface carburetor.

The resulting suspension or mixture is squeezed through the highly constricted orifice 24 into the intake at the engine side of the throttle 18. 50 The orifice 24 serves to meter the fuel component therethrough at a substantially constant rate, the constriction having frictional coefficients such as to allow the passage of a predetermined quantity of mixture, and no more, irre- 55

spective of variation in intake depression, the mixture being wire drawn, in effect, and issuing from the orifice 24 as a fine stream of atomized fuel particles.

- 5 Air inlet opening 26 is preferably somewhat larger than the metering jet opening 24, the opening 26 being adjusted in size so that the pressure reduction in chamber 22 is sufficient to raise fuel thereinto and maintain the level. 10 For example, in one type of engine the opening 24 was .014" in diameter and opening 26 was .022" in diameter. Satisfactory operation has been obtained with air inlet opening 26 of the order of .020" to .030" in diameter and with a 15 metering orifice 24 of the order of .013" to .016" in diameter. The orifices 24 and 26 preferably comprise replaceable jets for allowing adjustment of the orifice sizes, the adjustment of the jet 26 being principally relied on to determine 20 the pressure reduction in the chamber 22, and being also relied on to determine the mixture ratio, so as to obtain the best mixture ratio for any desired idling speed.

With the metering of idling fuel in the form of 25 air-fuel mixture through the orifice 24 with openings 24 and 26 of about the sizes above specified, I find that the quantity of fuel introduced into the intake at engine idling remains substantially constant over a considerable range of 30 variation of the intake depression, giving a smooth, steady idling even though there be a considerable fluctuation in intake depression.

The fuel supplied also remains constant when 35 excessive speeds are attained with closed throttle 18 during engine comedown periods, thereby preventing undue enrichment of the mixture liable to cause loading, crank case oil dilution, afterburning and other evils.

Location of the air inlet orifice 26 at a level 40 above the fuel exit orifice 24 increases the fuel discharged, and location of orifice 26 at a level below orifice 24 decreases the fuel discharged. However to maintain constant fuel flow, it is 45 preferable to have the air inlet 26 on a level with the exit orifice 24.

The relative areas of the orifices 24 and 26 are such as to cause the fuel to be supplied through orifice 24 not only at engine idling but also throughout substantially the fractional load 50 range of operation.

In order to prevent the chamber 22 from flooding and causing flow of solid liquid fuel through orifice 24, the passage 20 below the fuel level in chamber 16 is provided with a small metering 55 orifice or replaceable jet 28 which restricts the rate of fuel flow sufficiently to maintain a constant fuel level in the chamber 22 under various conditions of engine idling operation, insuring the supplying of fuel at a constant rate. With 60 the orifices 24 and 26 of about the diameters of the order above stated, a satisfactory diameter for the orifice 28 has been found to be .018" to .020".

Without the constricted metering orifice 28, 65 erratic fuel flow might at times occur. For example, if the engine is accelerating and the throttle is suddenly closed, the resulting high depression in the intake and fluctuation in fuel level in chamber 16 might cause chamber 22 to 70 flood above its normal level, closing the air inlet 26, and causing an unduly rich discharge of fuel. The provision of orifice 28 prevents, because of

the limited capacity of the orifice to allow fuel flow therethrough, sudden changes in fuel level in the chamber 22, making it possible to maintain a smooth, uniform idle.

At Fig. 2 I have shown a manual adjustment 5 for air inlet orifice 26, the orifice being adjusted by a needle valve 30 to control the pressure reduction in the chamber 22 and the quantity of fuel supplied.

By my invention I am able to maintain the 10 rate of fuel delivery at engine idling substantially constant over a wide range of variation or fluctuation in intake depression, the idling fuel mixture being prevented from becoming too rich, insuring smooth, steady engine idling, and preventing the detrimental effects above referred to.

With my idling fuel arrangement the throttle can be used to control the idling speed without causing variation in the rate of fuel delivery into the intake, and by proper selection of the size of 20 the air jet 26 or by adjustment of orifice 26^a, Fig. 2, the fuel quantity or mixture ratio can be controlled or adjusted for any idling speed.

Having thus described my invention what I claim and desire to secure by Letters Patent is: 25

1. Process of supplying charges for internal combustion engines comprising causing air to sweep over a concave meniscus of fuel, and drawing the resulting mixture through a highly constricted orifice subjected at the posterior side 30 to the pressure reduction in the intake at the engine side of the throttle, the quantity of air introduced being such as to produce at high depressions a pressure reduction at the anterior side of the discharge orifice elevating the fuel to 35 maintain the meniscus at a level in proximity to the air stream passing to said discharge orifice.

2. Process of supplying charges for internal combustion engines, comprising causing a stream 40 of air to sweep over a concave meniscus of fuel to thereby subject the fuel to the surface vaporizing effect of said stream of air, and discharging the resulting mixture through a constricted orifice into the region of reduced pressure at the engine side of the throttle, said fuel 45 being elevated by a pressure reduction at the anterior side of said discharge orifice sufficiently attenuated by the air introduction to maintain at high intake depressions a fuel level in the form of a concave meniscus in proximity to the air 50 stream passing to said discharge orifice.

3. Process of supplying charges for internal combustion engines comprising inducing a flow of air through a passage by the pressure reduction in the intake at the engine side of the 55 throttle, producing in a section of said passage, by relative constriction of orifices at the atmospheric and intake pressure reduction ends thereof, a lesser pressure reduction, lifting fuel by 60 said lesser pressure reduction at or near engine idling from a lower level to form a fuel level in the form of a concave meniscus in said passage section, subjecting the fuel at said fuel level to the action of the air sweeping thereover to form a fuel-air mixture, and discharging the mixture 65 thus formed through the constricted orifice at the intake pressure reduction end of the passage section to draw the mixture out into a stream of reduced cross-section for promoting fuel vaporization and to meter the fuel component. 70
